UNITED STATES PATENT OFFICE.

RICHARD DUGGAN, OF LAWRENCE, MASSACHUSETTS, ASSIGNOR TO
THOMAS HALL, OF SAME PLACE.

WOOL-OILING MACHINE.

SPECIFICATION forming part of Letters Patent No. 269,514, dated December 26, 1882.

Application filed June 29, 1882. (No model.)

To all whom it may concern:

Be it known that I, RICHARD DUGGAN, a citizen of the United States, residing at Lawrence, in the county of Essex and State of Massachusetts, have invented certain new and useful Improvements in Wool-Oiling Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to certain improvements in wool-oiling machines; and it has for its objects to provide for automatically supplying the oil from a tank or reservoir to the oiling-chamber, and for filling the tank without admission of air to the same, as more fully hereinafter specified. These objects I attain by the means illustrated in the accompanying drawings, in which—

Figure 1 represents a longitudinal vertical section of my improved apparatus on $x-x$ of Fig. 4. Fig. 2 is a vertical cross-section of the same on line $y-y$ of Fig. 1. Fig. 3 is an end elevation thereof. Fig. 3^a is a vertical section of the double tube N, as seen in Fig. 3. Fig. 4 is a horizontal section on $z-z$ of Fig. 1, and looking down upon the oiling-chamber and oiling devices.

The letter A indicates the oiling-chamber, which consists preferably of a semi-cylindrical vessel, having located within it a longitudinally-arranged cylinder, B, mounted on a shaft, C, journaled in suitable bearings and provided with a pulley, e, at one end, by means of which it may be rotated by a belt or band connecting with a suitable driving-wheel. The said vessel is provided at one side with an inclined corrugated chute, D, and with pivoted corrugated fingers E, to direct or control the discharge of the oil from the cylinder B.

The letter F indicates the tank or reservoir which contains the oil to be supplied to the oiling-chamber A. This tank F is mounted upon standards G, secured to the oiling-chamber A. The tank F is preferably cylindrical, but may be of any other convenient shape. Through one end of tank F extends a filling-

tube, H, provided with a funnel and strainer, I, at its upper end. The lower end of tube H terminates in the upper part of a chamber, K, from the lower part of which extends upward 55 a pipe, L, terminating at l in the upper part of the tank F in such manner that as the oil is fed into the filling-tube H it is discharged into the tank F through the pipe L without admitting any air.

M is a tube extending from the lower part of the tank F at one end to the oiling-chamber A below. Into tube M extends a double pipe, N, through a suitable screw-threaded aperture in the top of the tank. One branch of the 65 pipe N opens through a screw-cap, P, secured in the aperture. The other branch opens into the tank F at its upper end, n, near the aperture. The lower ends of the two branches terminate within the tube M, near its lower end, 70 to permit the escape of any air or other fluid which may be generated in the tank F.

R is a tube extending from a point above the level of the oil in tank F to the oiling-chamber A below, by means of which the air 75 necessary to permit the oil to flow automatically from the said tank F to the chamber A is admitted when the oil falls below the level of the lower end of said tube R at r, Figs. 1 and 4.

The wool is caused to move by any appropriate means below the chute D, and the apparatus is caused to operate in a corresponding motion by means of the pulley e on shaft C, and the cylinder B rotates, bringing the oil 85 up on its surface from the oiling-tank A, and the fingers E, resting by their own weight on cylinder B, take off the oil from the cylinder, and by the corrugations in the fingers and on the surface of the chute D it is conveyed in 90 drops regularly onto the wool passing below. The air-pipe N has one branch passing through the cap P at the top of the tank F, the other end opening into the tank F, near the top, so that the oil is allowed to run into the oiling-tank A from the filling-tube and funnel H until it comes in contact with the air-pipes N inside and at the bottom of the tube M. The arrangement of the several tubes is as follows: In filling the tank F the valve m is closed. The 95 oil passes down the funnel and supply-pipe H into the chamber K, where the condensed air 100

above the oil forces the oil up the pipe L free from air, and it overflows at the upper end, l, and falls into the tank F until the surface of the liquid rises up to the level of the pipe R 5 at r', when it will run down the pipe R and into the oiling-chamber A. The two pipes N unite at the bottom in tube M, and have been described above.

Having thus described my invention, what I 10 claim, and desire to secure by Letters Patent, is—

1. The combination, with the oiling-chamber A and its cylinder B, of the inclined corrugated chute D and the pivoted corrugated fingers 15 E, for controlling the flow of the oil, substantially as specified.

2. The combination, with the tank F, of the filling - tube H, provided with a funnel and strainer, and the chamber K at the lower end, 20 and an independent tube, L, leading into the upper part of the tank F from said chamber K,

substantially as and for the purpose described.

3. The combination, with the tank F and oiling-chamber A, of the connecting-tube M and inclosed double air-pipe N, communicating at 25 one end with the interior of tank F and external air above, and the other end communicating with the interior of the oil-chamber A, substantially as and for the purpose described.

4. The combination, with the tank F and oiling-chamber A, the connecting-tube M and inclosed double air-pipe N, of the tube R, leading 30 from the bottom of the tank F to the oiling-chamber A, substantially as and for the purpose described.

In testimony whereof I affix my signature in presence of two witnesses.

RICHARD DUGGAN.
